(57) **CLAIM**

The ornamental design for a feeder and waterer, as shown and described.

DESCRIPTION

FIG. 1 is a front perspective view of a feeder and waterer, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlargement of FIG. 1.

The broken lines in the drawings illustrate the portions of the feeder and waterer, which form no part of the claimed design.

The dot-dash lines in FIGS. 1 and 9 are used to indicate the area of the enlargement portion of the feeder and waterer, and form no part of the design claim.
